UNITED STATES PATENT OFFICE.

CHARLES ELMAR DAILEY, OF EAST LIVERPOOL, OHIO.

CAR-REPLACER.

SPECIFICATION forming part of Letters Patent No. 405,398, dated June 18, 1889.

Application filed December 13, 1888. Serial No. 293,478. (No model.)

To all whom it may concern:

Be it known that I, CHARLES ELMAR DAILEY, a citizen of the United States, residing at East Liverpool, in the county of Columbiana and State of Ohio, have invented certain new and useful Improvements in Railroad-Car Replacers; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 My invention relates to that class of car-replacers described in Patents Nos. 10,301 and 362,259, and its special object is to obviate certain objections thereto, as hereinafter described.

20 Figure 1 is a plan view, and Fig. 2 a cross-section on the dotted line $x x$ of Fig. 1.

In the drawings, A A' represent the main-track rails, and B the sleepers. On the outside of the right rail A, I secure by hooks H 25 a plate P, which widens gradually from front to rear and inclines downwardly until the broad end is quite or nearly flush with the top of the sleepers B. On this plate P, I arrange three guide-rails Q R S, so that there are, when taken in connection with rail A, three open spaces, in which the wheel of car 30 may run and be conducted up to and upon the said rail A. The middle guide-rail R is pivoted near its rear end and diagonally cut at

35 the front end, while the latter is held by a spring-bolt T to the outer guide-rail S. This outer guide-rail is extended forward at S' and there provided with the vertical guard-flange

S²; hence it will be seen that if the right car-wheel enters the space between the guard-rail Q and track-rail A it is guided directly upon rail A; but if it enters either of the other openings it is first conducted to the extension S', and thence to the rail A. If said car-wheel enters the opening between the guide-rails R S, the guide-rail R is pressed aside, but as soon as the wheel passes is drawn back by the spring-bolt. On the rail A, and opposite the plate P, I secure by hooks H a plate P', which inclines downwardly toward the other rail and widens rearwardly until it nearly touches rail A. On the sharp edge of plate P' is used a pin p, which bites on one of the sleepers B, so as to keep the plate from being moved forward with the car. 55 Plate P is also held by a subjacent wedge-clamp V.

I preferably set the plate P' one sleeper ahead of the plate P.

Having thus described all that is necessary to a full understanding of my invention, what I claim as new, and desire to protect by Letters Patent, is—

A car-replacer consisting of the two plates P P', the former provided with guide-rails Q 65 R S, and extension S', having the vertical guard-flange S², the middle guide-rail being rear pivoted and spring held in front to the outer guide-rail, as and for the purpose set forth.

In testimony whereof I affix my signature in presence of two witnesses.

CHARLES ELMAR DAILEY.
